UNITED STATES PATENT OFFICE.

CARLTON R. RADCLIFFE, OF NEW YORK, N. Y., ASSIGNEE, BY MESNE ASSIGNMENTS,
TO THE SCIENTIFIC RESEARCH CO., OF NEW YORK, N. Y., A CORPORATION OF NEW
YORK.

HYDRAULIC POWER-TRANSMITTING APPARATUS.

1,122,303.

Specification of Letters Patent.

Patented Dec. 29, 1914.

Application filed August 28, 1907. Serial No. 390,634.

To all whom it may concern:

Be it known that I, CARLTON R. RADCLIFFE, a citizen of the United States, and a resident of the city of New York, in the county of New York and State of New York, have invented certain new and useful Improvements in Hydraulic Power-Transmitting Apparatus, of which the following is a specification.

10 The present invention relates to power transmitting apparatus, by means of which the rotation of a driving member is imparted to a driven member through the medium of a suitable fluid.

15 More particularly the device relates to hydraulic power transmitting apparatus having independent rotatable driving and driven members, and means whereby the direction of rotation of the driven member 20 may be reversed on maintaining the direction of rotation of the driving member.

In some of the hydraulic power transmitting apparatus, as heretofore in use, in order to reverse the direction of rotation of the 25 driven member, it is necessary to reverse the direction of rotation of the driving member, as described in United States Letters Patent No. 984,849, granted to me Feb. 21, 1911, or in other words it is either necessary to reverse the direction of rotation of the engine 30 to which the power transmitting apparatus is connected, or other means must be provided, adapted to reverse the direction of rotation of the driving member. It is obvious 35 that such a reversal necessitates a rather complicated apparatus and a rather complicated engine, while it is obvious that the reversing means should be as simple as possible and not depend on the engine, operating the "driving member."

It is now the object of the present invention to provide a power transmitting apparatus, in which the direction of rotation of the driven member may be reversed at will, 45 on maintaining the direction of rotation of the driving member.

Speaking in general terms, the present invention consists of an impeller of a centrifugal pump, secured to a rotatable shaft, and operated by means of any suitable 50 source of power. The impeller, hereinafter to be referred to as the driving member, is inclosed by a fluid-tight casing. Within the

casing are loosely mounted two series of vanes, which vanes are similar to the vanes of a turbine. One series of these vanes is provided for the ahead direction and the other for the reverse direction. The casing is filled with a suitable fluid medium and, it will be seen that, in rotating the shaft and the impeller secured thereto, a motion is imparted to the fluid, which enters the vanes of the impeller, partakes of the rotation of the same, and leaves the vanes with a considerable amount of kinetic energy, due to its velocity of whirl and radial velocity. The kinetic energy of the water is then used for doing useful work, *i. e.* to rotate the driven member. The jets or streams of liquid, flowing from the vanes of the impeller, impinge one or the other series of vanes and transmit rotation to the driven member. It is obvious, that the directions in which these two series of vanes discharge the fluid are opposite to each other, therefore their blades are bent in opposite directions. But, since the driving member rotates always in the same direction, it is necessary to provide for the reverse vanes a plurality of deflectors, in order to change the direction of the fluid, when it is intended to reverse the direction of rotation of the driven member.

The invention is illustrated in the accompanying drawings, in which—

Figure 1 is a cross section of the apparatus parallel to the axis of the same, Fig. 2 is a similar section of a modification of the device, Figs. 3 and 4 are sections of the apparatus in lines A—A and B—B, respectively, and Fig. 5 shows another modification of the device.

1, in Fig. 1 indicates a rotatable shaft, journaled in bearings 2—2, which are supported by standards 3, the latter being secured to a base or frame 4.

An impeller 5, similar to an impeller of a centrifugal pump, is secured to the shaft 1 by any suitable means, as for instance in the present case by a key 6. The shaft and the impeller, secured thereto, may be rotated through the medium of a driving pulley 7 by any suitable source of power. The impeller 5 is formed of a number of radial vanes 8, or of curved vanes like those of a reaction turbine-wheel, and rotates in

the direction of the arrow shown in Figs. 3 and 4.

A fluid-tight casing or shell 9 is loosely mounted upon the shaft 1, and comprises two separate parts 10 and 11, secured together by screw bolts 12, or in any other suitable manner. A pulley 11' is secured to or made integral with the part 11 of the casing, and suitable to transmit power by means of a belt or any other flexible connection. The casing may be made fluid-tight in any manner well known in the art, as by means of stuffing boxes 13. Two independent series of vanes 14 and 15 are secured to the part 10 of the fluid-tight casing. These vanes are similar to the vanes of the runner of an outflow turbine, and are as shown in Figs. 3 and 4 bent in opposite directions. The vanes 14 serve for the ahead direction, while vanes 15 are provided for the reverse direction. As shown in Fig. 3, the liquid, leaving the vanes of the impeller, enters the vanes of the driven member in the direction of rotation of the impeller, the driven member will, therefore, rotate in the direction indicated by the arrow in Fig. 3. To reverse the driven member, it is necessary that the liquid should leave the driven member in a direction opposite to the direction, shown in Fig. 3. Therefore the vanes for the reverse direction must be bent in a direction opposite to the direction for the ahead running. But as the impeller rotates always in the same direction, the liquid could not properly enter the oppositely bent vanes. Consequently a plurality of deflectors must be provided, directing the liquid from the impeller to the vanes of the driven member under the proper angle. The deflector is indicated at 16, and comprises a plurality of vanes secured to a spider 17, which is loosely mounted on the shaft 1. To this spider may be applied a brake mechanism, comprising a wheel 18 and a brake-band 19, for a purpose hereinafter to be explained.

In order to bring the runner in operative position to either of the series of vanes 14 or 15, a shifting lever 20 is fulcrumed at 21 to the standard 3, and operatively connected to the shaft 1. By means of this lever the runner 5 may be longitudinally shifted relative to the vanes of the driven member, so that the operator may at will direct the fluid, leaving the vanes of the impeller, to either of the series of vanes 14 or 15. A locking device 22 is provided for the purpose of locking the runner against longitudinal movement in some intermediate position.

The runner 8 is provided with a heavy portion 23, acting as a fly-wheel.

The casing 9 may be filled with a suitable fluid through an opening 24 in the casing, and adapted to be closed by a plug 24'.

The operation of the apparatus so far described is as follows: Power is applied to the shaft through the driving pulley 7, and rotates the impeller secured thereto. Supposing now, that the impeller is in the position shown in dotted lines in Fig. 1, it will be seen, that the liquid enters the "eye" of the impeller and will rotate with the same. The centrifugal force forces liquid toward the periphery of the impeller through the vanes 8 and imparts to the same a velocity of whirl and radial velocity. The liquid flows in jets or streams to the vanes 14 of the driven member (Fig. 3), impinges on the same and imparts to the same rotation. The liquid then leaves the vanes with a relative velocity which is practically zero and enters again the impeller to start again the circulation, described hereinbefore.

It will be observed that the apparatus described acts like an outward-flow reaction turbine, with the exception that the energy, operating the same, is created mechanically by the impeller; in other words it is a turbine, having rotatable guides adapted to create a "head". The fluid leaves the impeller practically tangentially, and enters the vanes of the runner, changing the direction of flow as it leaves the same, and exerts a pressure against the surfaces of the vanes, moving thereby the runner. Shifting now the shaft and the impeller, secured thereto, so as to bring the vanes of the impeller in operative position relative to the vanes 15 (Figs. 1 and 4) of the driven member, the direction of action of the fluid will be reversed relative to the direction described in connection with Fig. 3. The liquid, leaving the vanes of the impeller, will enter the vanes 16 of the deflector, be directed to the vanes 15 and leave these vanes in a direction opposite to the direction in which it leaves the vanes 14, the driven member will therefore reverse its direction of rotation.

It is obvious that the deflector should be held against rotation, when the driven member is running in the reverse direction. To hold the deflector against rotation the brake 19 is applied to the wheel 18, secured to the deflector.

Fig. 2 shows a modification of the device, in which the casing 9 is longitudinally movable relative to the runner 5. In this case the deflector 16' is secured to the casing, while the vanes 14' and 15' are secured to a spider 25, moving longitudinally with the casing, when the same is shifted. The brake 19 is in this case applied to the casing 9. A heavy annular portion 26 is arranged on the casing, adapted to close the outlets of the vanes of the impeller, when the same is in its middle position. This position is shown in Fig. 2 and may be termed the "neutral position". It may be observed, that in this

position, although the driving member rotates, the driven member will be in its position of rest, since no water enters the vanes 14' or 15' respectively. Shifting the casing and the spider, moving therewith, so as to bring the vanes 14' in operative position relative to the impeller, the spider will run in the ahead direction, while when the vanes 15' and deflector 16' are brought in operative position to the vanes of the impeller and the deflector 16' held by means of the brake-band 19 against rotation, the spider 25, that is the driven member, will run in the reverse direction. It will be observed, 15 that the heavy annular portion 26 may act as a gate, by partially closing the outlets of the vanes of the runner, when the spider is moved longitudinally and locked by means of locking mechanism 27 in an intermediate 20 position. By means of this gate the speed of the driven member may be varied at will. In partially closing the outlets of the vanes of the runner, only a predetermined quantity of water, leaving the vanes of the impeller, will enter the vanes of the runner. 25 Since the quantity of liquid is decreased, the speed of the driven member will be decreased. In the device shown in Fig. 1 the impeller may be shifted, so as to vary the 30 speed of the driven member.

It is a well known fact, that the torque of the runner of a turbine is a function of the difference of speeds of the guides and the runner. The greater the difference, the 35 greater is the torque. In this particular case the torque is a function of the difference of the speeds of the impeller and the driven member, which may be called the "runner". The speed of the runner may be 40 varied at will by varying the speed of the prime mover, acting upon the driving member; it will be seen, therefore, that the torque of the apparatus may be varied in this way. But as the speed of the driven 45 member may be also varied on maintaining the speed of the driving member, the torque of the driven member may be, therefore, varied by varying the speed of the same. It will be noticed, that the torque of the driven 50 member may also be varied automatically by the load applied to the same. The speed of the driven member decreases as the load increases, and, since the torque increases as the difference of the speed of the driving 55 and driven members decreases, it will be seen that the torque increases as the load increases.

Fig. 5 is a modification of the device, in which the casing 28 is stationary and carries 60 the shaft 1 in the bearings 29 and 30. In this case the impeller 31 is slightly modified so as to discharge the fluid, flowing through the vanes thereof, toward the axis of the same. The vanes 14 for the ahead direction 65 and vanes 15 for the reverse direction are

secured to a disk 32, while the deflector 16 is secured to the casing 28. It will be seen, that no brake is needed for the deflector in this device, since the casing, to which the same is secured, is stationary. The shaft 70 and impeller secured thereto may be shifted by means of the lever 33. A latch 34 is used to set the free end of the lever 33 to any of the notches 35 of the segment 36, so that the impeller may occupy any intermediate position. 75 This device may be compared with an inward-flow turbine, since the water or liquid, leaving the vanes, is discharged inwardly toward the axis of the apparatus. The operation of this device may be easily 80 understood from the description of the other modifications, forming part of this application.

It is to be observed that in the devices shown in Figs. 1 and 2 of the drawings it is 85 possible to vary the speed of the driven member when the latter rotates in a direction opposite to the impeller and the vanes of said impeller fully register with the vanes of the deflector. For this purpose it 90 becomes only necessary to permit the deflector to slip by loosening the grip of the brake band 19 to the desired extent. The maximum speed, of course, will be obtained when the deflector is kept stationary. 95

What I claim is:

1. In a hydraulic power transmitting apparatus, the combination with a rotatable driving member, of a driven member adapted to rotate independently of said driving member, a fluid-tight casing inclosing said members and adapted to contain a liquid, a plurality of vanes on said driving member, two independent series of vanes on said driven member arranged concentrically with the vanes of said driving member, a deflector, the vanes of said driving member being adapted to direct liquid to either series of vanes to said driven member either directly or by means of said deflector, and to rotate said driven member in either direction. 100

2. In a hydraulic power transmitting apparatus, the combination with a primary turbine wheel, of a secondary turbine wheel 115 comprising two series of vanes arranged concentrically with the vanes of said primary wheel, and means adapted to be kept against rotation to reverse the direction of rotation of said secondary wheel on maintaining the direction of rotation of said primary wheel, arranged concentrically with the vanes of said driving member, substantially as described. 120

3. In a hydraulic power transmitting apparatus, the combination with a primary turbine wheel, of a secondary turbine wheel comprising two series of vanes arranged concentrically with the vanes of said primary wheel, one series serving for the ahead di- 125

rection and the other for the reverse direction of said secondary wheel, and means interposed between said primary wheel and the reverse vanes of said secondary wheel to change the direction of the flow of the liquid issuing from the primary wheel, substantially as and for the purpose specified.

4. In a hydraulic power transmitting apparatus, the combination with a primary 10 turbine wheel, of a secondary turbine wheel comprising two series of vanes arranged concentrically with the vanes of said primary wheel, one series serving for the ahead direction and the other for the reverse direction of said secondary wheel, means interposed between said primary wheel and the reverse vanes to change the direction of the flow of water issuing from the primary wheel, and means for keeping said interposed means against rotation.

5. In a hydraulic power transmitting apparatus, the combination with a primary turbine wheel, of a secondary turbine wheel comprising two series of vanes arranged 25 concentrically with the vanes of said primary wheel, a deflector, and means adapted to direct the operating liquid issuing from said primary wheel to one series of vanes of said secondary wheel whereby the same is 30 rotated in the direction of rotation of the primary wheel, or direct the liquid through said deflector to the other series of vanes of the secondary wheel whereby the latter reverses its direction of rotation.

35 6. In a hydraulic power transmitting apparatus, the combination with a primary turbine wheel, of a secondary turbine wheel comprising two independent series of vanes, one series serving for the ahead direction 40 and the other for the reverse direction of said secondary wheel, means interposed between said primary wheel and the reverse vanes of said secondary wheel to change the direction of the flow of water issuing from 45 said primary wheel, and means for varying the relative position of said primary and said secondary wheels, for the purpose described.

7. In a hydraulic power transmitting apparatus, the combination with a primary 50 turbine wheel, of a secondary turbine wheel comprising two series of vanes having different vane curvatures, one series of vanes serving for the ahead direction of said secondary wheel and the other for the reverse direction, a deflector interposed between the primary wheel and the reverse vanes of the secondary wheel and comprising a plurality 55 of vanes having curvatures in a direction opposite to the direction of curvature of the reverse vanes of the secondary wheel, and means for changing the relative position of said primary and secondary wheels, whereby the liquid issuing from said primary 60 wheel may be directed to the ahead

70 vanes of the secondary wheel or through the deflector to the reverse vanes of said secondary wheel.

8. In a hydraulic power transmitting apparatus, the combination with a primary 75 turbine wheel, of a secondary turbine wheel comprising two series of vanes having different vane curvatures, one series of vanes serving for the ahead direction of said secondary wheel and the other for the reverse 80 direction, a deflector interposed between the primary wheel and the reverse vanes of the secondary wheel and comprising a plurality of vanes having curvatures in a direction opposite to the direction of curvature of the 85 reverse vanes of the secondary wheel, means for changing the relative position of said primary and secondary wheels, whereby the liquid issuing from said primary wheel may be directed to the ahead vanes of the secondary wheel or through the deflector to the reverse vanes of said secondary wheel, and means for arresting the rotation of said deflector.

9. In a hydraulic power transmitting apparatus, the combination with a primary 90 turbine wheel, of a secondary turbine wheel comprising two series of vanes, a deflector, said primary wheel being adapted to direct the operating liquid issuing from said primary wheel directly to one series of vanes of said secondary wheel whereby the same is 95 rotated in the direction of rotation of the primary wheel, or direct the liquid through said deflector to the other series of vanes of the secondary wheel whereby the latter reverses its direction of rotation, and means for varying the amount of liquid flowing 100 from said primary wheel to either series of vanes at will.

10. In a hydraulic power transmitting apparatus, the combination with a primary shaft, of a secondary shaft, means for transmitting power from said primary shaft to said secondary shaft, comprising a primary 110 turbine wheel, a secondary turbine wheel, and a rotatable guide wheel juxtaposed to said first mentioned wheels, and means for holding said guide wheel against motion.

11. In a hydraulic power transmitting apparatus, the combination with a primary shaft, of a secondary shaft, means for transmitting power from said primary shaft to said secondary shaft, comprising a primary 115 turbine wheel, a secondary turbine wheel, and a rotatable guide wheel juxtaposed to said first mentioned wheels and receiving fluid directly from one and delivering directly to the other, and means for holding 120 said guide wheel against motion.

12. A hydraulic power transmitting apparatus, the combination with a centrifugal pump impeller, of a turbine rotor, a rotatable guide wheel interposed therebetween for receiving fluid directly from the said 130

impeller and guiding it to said rotor to rotate said rotor in a direction opposite to that of said impeller, and a brake adapted to be applied to said guide wheel to hold it, at will, against motion or to permit it to slip.

Signed at New York, in the county of

New York and State of New York, this 24th day of August, A. D. 1907.
